A radio antenna having high gain to aid in receiving signals from distant stations and having a relatively low power input. The antenna is of the type having a base structure of equilateral triangular form, the top apex of which is connected to a vertical supporting mast. The conductors are arranged at the corners of the base triangle and have alternating vertical and horizontal sections spiraling around the central mast. The vertical sections are arranged at the corners of an equilateral triangle.

SHORT WAVE BROADCAST ANTENNA

Nils E. Lindenblad, Port Jefferson, N. Y., assignor to Radio Corporation of America, a corporation of Delaware

Application October 8, 1938, Serial No. 233,894

12 Claims.

(Cl. 250—33)

The present invention relates to radio antennas and, more particularly, to short wave antennas capable of giving a substantially uniform radiation toward all points on the horizon. The use of very high frequency energy for radio communication is exceedingly desirable because of the great distances covered by comparatively small amounts of energy. However, the regular use of short waves for communication is seriously handicapped by the severe fading encountered, by phase distortion and echo effects produced by the signal travelling over the plurality of paths of different length due to the signal being reflected from varied reflecting surfaces encountered. This is likewise true even at such high frequencies that the Heaviside layer ceases to function as a reflector or refractor, or both, at such frequencies buildings and other structures then act as reflectors. My present invention reduces these difficulties by transmitting a wave polarized in both horizontal and vertical planes instead of in a single plane only. Depending upon the amplitude and phase relationship between the two components the resultant wave may be either merely tilted or it may be rotary. If the wave peaks of the two components arrive 90 degrees out of phase and have equal amplitudes, the result will be a circularly polarized wave. If the amplitudes are unequal the result will be elliptically polarized.

My invention results in a more uniform field strength distribution over land and water since reception over water is, in general, better when a vertical polarized signal is used and horizontal polarization gives better results over land. A circularly polarized wave containing both horizontal and vertical polarized components will, of course, give the advantages of each.

My invention has as an object the attainment of the foregoing advantages.

A further object of my invention is to provide an antenna structure for radiating electro magnetic waves having a varying plane of polarization.

Another object of my invention is to provide an antenna which radiates a radio wave with a varying plane of polarization having an intrinsic relationship to the frequency of the radiated waves.

Still a further object of my invention is to provide a short wave antenna which is mechanically strong and is entirely electrically grounded as a protection against lightning.

The antenna of my invention comprises a plurality of conductors arranged at the corners of an equilateral figure and having alternating ver-

tical and horizontal half wave sections arranged spirally around the circumference of said figure. In a preferred form of my invention the vertical conductors are arranged at the corners of an equilateral triangle, since, as I have disclosed in my copending application No. 76,745, filed April 28, 1936, the triangular arrangement readily gives a uniform radiation in a horizontal plane while other arrangements may not readily do so.

The following description is accompanied by drawings in which Figure 1 shows an embodiment of my invention, while Figures 2, 3, 4 and 5 are vector diagrams showing the operation of my invention. In Figure 1 reference numerals 1, 2 and 3 indicate the three radiating conductors of my invention which are located at the corners of a horizontally disposed equilateral triangle. Vertically upward from point 1 the conductor extends a distance equal to a half the length of the operating wave as radiator 11. At the top end of 11 and at right angles thereto, the conductor continues as a horizontal half wave radiator 12 which lies parallel to one side of the equilateral triangle. The conductor then extends upward as at 13 and continues spirally around the antenna through half wave radiating sections 14, 15 and 16. Conductors 2 and 3 at the other corners of the base triangle similarly advance spirally upward around central mast 5. At voltage nodal points of each of the half wave sections conducting supports 6 are attached. The other end of each of the supports 6 is attached to the mast 5. The central supporting mast 5 is preferably constructed of a conducting material whereby the entire antenna may be grounded as a protection against lightning strokes.

By reference to the diagrams in Figures 2, 3, 4 and 5, it will be seen how the resultant radiation from all of the vertical members becomes approximately 90 degrees out of phase with the resultant from all the horizontal members. The combination of these two resultants in space results in a substantially circularly polarized field.

Referring to Figure 2, which shows the effect of the radiation from 3 of the vertical members 11, 21 and 31, for instance, in a phase reference line or wave front parallel to a plane passing through members 11 and 31. The effective radiation from each of the members 11, 21 and 31 is represented in Figure 2 by the vectors A₁, A₂ and A₃. Since vectors A₁ and A₂ are in the same direction and originate from the same plane they add in direct phase relationship. The radiation represented by vector A₂, by the time it has advanced to the phase reference line X₁, X₁ will be effective in

a direction as shown by the vector diagram in the lower part of Figure 2. The resultant radiation is denoted by reference letter R and has an amplitude equal to 1.162 times the radiation from any individual vertical conductor. The phase angle of the resultant as shown by the vector diagram is approximately -20 degrees, 30 minutes. Similarly, the analysis of the radiation from the horizontal members 12, 22 and 32, due to the currents I, is shown in Figure 3. The same phase reference line is taken as in Figure 2. Here, it will be seen, the entire radiation from radiator 32 is effective in the said direction. The portion of the radiation from each of radiators 12 and 22, which is effective in that direction, is represented by the vectors $A_{12}\sin.30$ degrees and vector $A_{22}\sin.30$ degrees. These two vectors will add in phase and by the time their resultant has reached the phase reference line X_2 , X_2 will be in a direction as shown by the vector diagram in the lower part of Figure 3. This resultant will combine with the radiation A_{32} to form the resultant R having an amplitude equal to 1.275 times the radiation from any individual conductor and at a relative phase angle of 51 degrees and 32 minutes.

From a consideration of these two diagrams it will be seen that the time phase relationship between the radiation from the vertical members and the horizontal members is approximately 73 degrees in the particular reference line chosen. This angle does not depart too far from the 90 degree phase relationship required for perfect circular polarization.

Figures 4 and 5 similarly analyze the radiation in a reference plane which is perpendicular to a plane passing through conductors 11, 31.

In Figure 4 it will be seen that the radiation A_1 from conductor 11 and the radiation A_3 from conductor 31 are 180 degrees out of phase due to the conductors being a half wave apart and therefore cancel, as far as this reference line is considered. The effective radiation from A_2 which, by the time it has advanced to the reference plane Z_1 , Z_1 , has a phase angle of -90 degrees. The amplitude, of course, is equal to the radiation from a single conductor, as is shown by the vector diagram in the lower part of Figure 4.

As shown in Figure 5, the radiation from the horizontal conductor 32 is ineffective in the reference line Z_2 , Z_2 . The effective radiation from conductors 12 and 22 is equal to $A_{12}\sin.60$ degrees and $A_{22}\sin.60$ degrees. These combine, as shown in the vector diagram in the lower part of Figure 5, to form a resultant R which is equal to 1.225 times the radiation from a single conductor and having a relative phase angle of zero degrees. It will be seen that a perfect phase displacement of 90 degrees exists between the horizontal and vertical radiation along the reference line chosen in this example. The radiation in the vertical members is exactly equal to unity and that from the horizontal members is only slightly larger than unity so a substantially circular polarization is obtained along this plane.

The analysis of the relationship for the two directions of wave fronts indicated by reference lines X and Z in Figures 2 to 5 are the extreme limits within which the field varies. At any other intermediate direction the resultant field will in amplitude and phase relationship fall somewhere between these two extreme limits. The radiators may be slightly bent or they may be tilted so that even more accurate circular polarization may be obtained in all directions. Such procedure, how-

ever, would be of only slight practical value since the construction shown and described heretofore is sufficiently accurate for all practical purposes.

While I have shown and particularly described an embodiment of my invention, it is to be definitely understood that my invention is not limited thereto but that modifications within the scope of my invention may be made.

I claim:

1. An antenna comprising a plurality of radiating conductors passing through the corners of a horizontal equilateral triangle having the length of its sides equal to a half the length of the operating wave, and alternately extending vertically a distance equal to a half the length of the operating wave and horizontally in vertical planes passing through the sides of said triangle whereby each of said radiating conductors forms a stepped helix about a vertical center axis passing through the center of said triangle. 20

2. An antenna comprising a plurality of radiating conductors passing through the corners of a horizontal equilateral triangle having the length of its sides equal to a half the length of the operating wave and alternately extending vertically a distance equal to a half the length of the operating wave and horizontally in vertical planes passing through the sides of said triangle whereby each of said radiating conductors forms a stepped helix about a supporting mast passing through 30 the center of said triangle.

3. An antenna comprising a plurality of radiating conductors passing through the corners of a horizontal equilateral triangle having the length of its sides equal to a half the length of the operating wave and alternately extending vertically a distance equal to a half the length of the operating wave and horizontally in vertical planes passing through the sides of said triangle whereby each of said radiating conductors forms a stepped helix about a supporting mast passing through the center of said triangle, and supporting arms connected to said mast at the midpoints of each of said half wave sections. 35

4. An antenna comprising a plurality of radiating conductors passing through the corners of a horizontal equilateral triangle having the length of its sides equal to a half the length of the operating wave and alternately extending vertically a distance equal to a half the length of the operating wave and horizontally in vertical planes passing through the sides of said triangle whereby each of said radiating conductors forms a stepped helix about a supporting mast passing through the center of said triangle, and supporting arms connected to said mast at the midpoints of each of said half wave sections. 45

5. An antenna comprising a plurality of radiating conductors passing through the corners of a horizontal equilateral triangle having the length of its sides equal to a half the length of the operating wave and alternately extending vertically a distance equal to a half the length of the operating wave and horizontally in vertical planes passing through the sides of said triangle whereby each of said radiating conductors forms a stepped helix about a metallic supporting mast passing through the center of said triangle, and conductive supporting arms connected to said mast and to each of said half wave portions. 60

6. An antenna comprising several groups of vertical radiators each having a length equal to a half the length of the operating wave, the radiators of each group being arranged in a common vertical axis and several groups of horizontal ra- 65

70

75

diators each having a length equal to a half the length of the operating wave, each group of horizontal radiators being arranged in a plane passing through two adjacent vertical axes and means for cophasally energizing all of said radiators.

7. An antenna comprising several groups of vertical radiators each having a length equal to a half the length of the operating wave, the radiators of each group being arranged in a common vertical axis and several groups of horizontal radiators each having a length equal to a half the length of the operating wave, each group of horizontal radiators being arranged in a plane passing through two adjacent vertical axes, each of the horizontal radiators forming a connection between one of the vertical radiators in one of said groups of vertical radiators and the next higher vertical radiator in the adjacent group.

8. An antenna comprising several groups of vertical radiators each having a length equal to a half the length of the operating wave, the radiators of each group being arranged in a common vertical axis and several groups of horizontal radiators each having a length equal to a half the length of the operating wave, each group of horizontal radiators being arranged in a plane passing through two adjacent vertical axes, each of the horizontal radiators forming a connection between one of the vertical radiators in one of said groups of vertical radiators and the next higher vertical radiator in the adjacent group.

9. An antenna comprising three groups of vertical radiators, each having a length equal to a half the length of the operating wave, the radiators of each group being arranged in a common vertical axis and three groups of horizontal radiators, each radiator having a length equal to a half the length of the operating wave, each group of horizontal radiators being arranged in a plane passing through two adjacent vertical axis and means for energizing each of said radiators in the same phase relationship.

10. An antenna comprising three groups of vertical radiators, each having a length equal to a

half the length of the operating wave, the radiators of each group being arranged on a common vertical axis and three groups of horizontal radiators each having a length equal to a half the length of the operating wave, each group of horizontal radiators being arranged in a plane passing through two adjacent vertical axes, each of the horizontal radiators forming a connection between one of the vertical radiators in one of said groups of vertical radiators and the next higher vertical radiator in the adjacent group, each of said radiators being cophasally energized.

11. An antenna comprising three groups of vertical radiators, each having a length equal to a half the length of the operating wave, the radiators of each group being arranged on a common vertical axis and three groups of horizontal radiators each having a length equal to a half the length of the operating wave, each group of horizontal radiators being arranged in a plane passing through two adjacent vertical axes, each of the horizontal radiators forming a connection between one of the vertical radiators in one of said groups of vertical radiators and the next higher vertical radiator in the adjacent group, each of said radiators being cophasally energized.

12. An antenna comprising three groups of vertical radiators, each having a length equal to a half the length of the operating wave, the radiators of each group being arranged on a common vertical axis and three groups of horizontal radiators each having a length equal to a half the length of the operating wave, each group of horizontal radiators being arranged in a plane passing through two adjacent vertical axes, each of the horizontal radiators forming a connection between one of the vertical radiators in one of said groups of vertical radiators and the next higher vertical radiator in the adjacent group, each of said radiators being cophasally energized, and conductive supporting means connected to the midpoints of each of said radiators.
